ABSTRACT OF THE DISCLOSURE

A vacuum failure stop motion device particularly adapted for use with a vacuum take-down system associated with circular knitting machines, the device having a chamber, the bore of which is substantially perpendicular to the axis of the evacuating tube of the vacuum system. The chamber contains a moveable piston which in turn is connected to the actuating finger of a switching device so that a change in the vacuum magnitude within the evacuating tube is sensed by the piston which moves within the chamber and displaces the finger to actuate the switch and thus terminate the operation of the machine.

Background, brief summary and objectives
of the invention

A number of machines used in the production of fabric and garments are sensitive to malfunctions to the extent that an interruption in the machine operation, a defect in the partially or finally completed product or an inaccurate or improper adjustment or setting will damage the machine, the product or both. For example, a knitting machine for producing ladies hosiery and the hosiery produced thereon are especially sensitive to sequential product withdrawal because a stocking which is not drawn away from the knitting instrumentalities properly can cause substantial damage to the machine if it continues to operate and will, itself, obviously become damaged. The present invention relates to an apparatus which can be attached to conventional machines such as those used in the production of apparel for controlling machine operation and especially to a device which can be attached to a conventional circular knitting machine that will deactivate the machine and prevent machine or garment damage when a malfunction occurs.

It is conventional practice to include on a circular knitting machine a device or means for applying tension downwardly on the hosiery being knit to ensure consistent and reliable stitch formation. A number of mechanical tensioning devices are often utilized, and in many cases, a flow of air is used to tension the fabric during the knitting operation. The vacuum or suction type tensioning device is quite effective in pulling the stocking away from the knitting needles to achieve the desired result.

Unfortunately, these vacuum devices, which are in quite widespread use, occasionally fail, either because of a radical fluctuation in pressure supply or because one or more of the article-carrying tubes on one or more of the machines becomes blocked when a knit stocking is not ejected properly. In such instances, the operation of the machine is impaired because the next stocking is started without the previous stocking being removed. When the previous stocking is not cleared from the needles in a satisfactory manner, commencement of the knitting operation for the next stocking can lead to a breakage of knitting needles requiring considerable downtime and maintenance to correct as well as a loss of the stocking involved.

To monitor the conventional suction system often used for the stocking takedown operation and to prevent damage to machines and the stockings under construction in

the event the vacuum system is activated for one reason or another, the present invention operates to shut down the knitting machine in the event the vacuum fails or varies greatly for any reason. The device is generally comprised of a small chamber communicating with the evacuating tube of the vacuum system leading from the knitting machine in which is carried a displaceable baffle. A piston rod connects with the baffle and extends outwardly from the chamber. Air movement to the chamber from the evacuation tube is through a series of apertures provided in the wall of the main tube. An activating device is positioned adjacent the chamber, and a conventional microswitch or other suitable activating and deactivating mechanism is preferred. The switch contains a moveable finger which functions as an operating or triggering device and is connected to the free end of the piston rod. So long as a vacuum is present in the evacuating tube of the suction system, the baffle and connecting rod will be drawn toward the main tube and hold the switching device through the movable finger in the open (or closed) position. Upon failure of the vacuum, the piston will be urged away from the main tube by the spring of the moveable finger of the switch. Thus the switch will close (or open) the circuit will become deenergized and this deenergization through the proper circuit arrangement will in turn deactivate the circular knitting machine.

From the foregoing discussion, it is clear that a primary object of the present invention is to provide a vacuum failure stop motion device of the type described which will effectively terminate the operation of a textile machine upon failure of the vacuum system when articles of apparel are not sequentially and properly removed as produced.

Another object of the present invention is to provide a vacuum failure stop motion device of the type described which is particularly adaptable to circular knitting machines for knitting tubular articles utilizing vacuum take down systems that draw the knitted articles away from the knitting instrumentalities.

Yet another object of the present invention is to provide a device of the type described which is extremely simple in construction, inexpensive to manufacture and reliable in operation.

A further object of the present invention is to provide a device of the type described which can be installed on conventional circular knitting machines embodying a vacuum take down system without any substantial modification being made on the machine or the vacuum system.

These and other objects and advantages of the invention will be apparent from the following description taken in conjunction with the accompanying drawings wherein like characters of reference designate like parts throughout the several views.

55 Figure description

FIG. 1 is a perspective, fragmentary view of a circular knitting machine illustrating one application of the present invention as applied to the suction take down system of a circular knitting machine.

60 FIG. 2 is a perspective, fragmentary and enlarged view of the vacuum failure stop motion device comprising the present invention and its association with the evacuating tube of a vacuum system such as used with circular knitting machines.

65 Detailed description of the invention

The present invention is a sensing device which can be applied to a conventional circular knitting machine utilizing a vacuum take-down system that is adapted to stop the machine when the vacuum system malfunctions for one reason or another or the magnitude of the vacuum

within that system fluctuates beyond established limits. Referring to the drawings and particularly to FIG. 1, a conventional circular knitting machine shown generally as 10 has a frame 12 and a fabric receiving tube 14 which is connected to a sealed tubular member 16 serving as the commencement of the evacuating tube generally indicated as 18. During the machine operation as the stocking is being knit, a vacuum is established from a remote source (not shown) within the evacuating tube system 18 to draw down the stocking as it is lengthened within the tube 14 by the knitting operation. The stocking extends downwardly through the initial tubular member 16 because of the vacuum existing therein as a result of suction from the remote source. The entire tubular system is sealed so that maximum suction within the system is experienced.

Normally the stocking, upon completion of the knitting operation, will be released from the needles and will be taken up through the tubular system 18 into the main vacuum trunk line 20. The trunk line extends to a receptacle collecting the knit garments from one or more knitting machines. The machines are arranged to deposit the knit stockings into the trunk line by a connecting section 22. So long as the vacuum system is operating properly, each independently knit stocking is sequentially discharged from the knitting instrumentalities of the machine and introduced into the main vacuum trunk line 20 for subsequent collection at a remote location by a suitable receptacle.

In the event the vacuum system fails or decreases in magnitude to the extent that the stocking being knit is no longer consistently drawn downwardly from the knitting needles, the knitting operation is impaired and the lack of tension on the stocking being knit can eventually lead to needle damage, stocking destruction and other machine impairment.

The present invention, while adaptable to any suitable machine wherein knitted articles are sequentially manufactured and discharged from the components of the machine, is particularly suitable for use with circular knitting machines for manufacturing hosiery having vacuum take-down systems such as that illustrated in FIG. 1. The stop motion device shown generally as 24 is comprised of a chamber 26 the longitudinal axis of which is substantially perpendicular to the axis of the evacuating tube section 28 to which the chamber is affixed. Communication from the interior of the chamber 26 to the tube section 28 is through a plurality of apertures 30 drilled in the wall of section 28 in any suitable or desired arrangement. The rearward portion 32 of the chamber 26 is bonded or otherwise affixed to one face 33 of an angular member 34 which is either integrally or articulately formed in the manner shown in FIG. 2. A suitable switching mechanism shown generally as 36 is then affixed to one surface of member 34 in a suitable manner so that a moveable switch-operating finger 38 extends upwardly to the axis of chamber 26. An electrical microswitch such as that made by Honeywell and designated type BZ RW performs very satisfactorily in this environment though obviously any number of commercially available microswitches having conventional operating characteristics would be equally effective.

A baffle 40 which forms a piston within chamber 26 is positioned to seal generally the chamber as shown. A piston rod 42 connects with the baffle 40 and extends rearwardly through an aperture 44 in face 33 of member 34 and provides an attaching point for linkage 46 that is secured to the moveable finger 38 of the switch 36. The switch control circuit represented by conductors 48 and 50 provides the knitting machine motor control.

So long as the vacuum system is operating in a normal manner, suction is present in the tubes 20, 22 and 24 and particularly, for illustrative purposes, in tube section 28 of FIG. 2. A vacuum in tube section 28 draws

the baffle 40 toward the section because of the apertures 39 present in the segment wall, and this holds the finger 38 of the switch 36 in a position that keeps the machine control circuit in an energized or operating state. In the event the vacuum system fails and no vacuum is present in tube section 28, the spring of the finger 38 will urge the piston rod 42 and baffle 40 away from the tube section 28. Thus in this instance, the switch will be actuated and the stop motion circuit formed by conductors 48 and 50 will close or open as the case may be and terminate the operation of the knitting machine.

The device constituting the present invention can obviously be installed on each singularly driven knitting machine. When a plurality of machines are driven from a 15 remotely located motor through a common shaft, the control circuit of each machine may be designated to disengage a clutch mechanism that drives each machine. It is also practicable and desirable to provide some of the 20 stop motion devices on the vacuum trunk line 20 communicating with a line of machines so that a failure of the main suction will stop the common drive shaft by switching off the main electric motor whose control circuit is actuated by a switch such as designated 36.

Though the present invention is very adaptable to any 25 number of industrial and technical applications, it is particularly appropriate for controlling circular knitting machines which embody or employ a vacuum system to draw down the garment being knit and thus provide uniform tension which is so necessary for a successful knitting 30 operation.

While there has been described a preferred embodiment of a vacuum failure stop motion device, obviously many variations and modifications may be made in the chamber, the switching device and the baffle as well as 35 other components without departing from the spirit and purpose of the invention. Such modifications are contemplated and are considered within the scope of the appended claims.

I claim:

40 1. A vacuum failure stop motion device associated with a vacuum system maintaining a continuous vacuum within an evacuating tube in combination with a circular knitting machine, said device comprising: a chamber 45 communicating with the evacuating tube; activating means positioned adjacent said chamber moveable from an active to an inactive position; piston means moveable within said chamber communicating with said activating means, said piston means responsive to at least one 50 change in the vacuum magnitude to actuate said activating means.

2. A device is claimed in claim 1, said chamber having vacuum-sensed apertures opening into the tube to reflect a change in vacuum magnitude in the chamber interior.

55 3. A device is claimed in claim 1, said activating means including a switch having a moveable finger responsively activating and deactivating said switch upon displacement through a predetermined distance.

4. A device is claimed in claim 1, said piston means including a baffle and a piston rod connecting said baffle with said activating means.

60 5. A device is claimed in claim 3, said piston means including a baffle and a piston rod connecting said baffle and said switch moveable finger.

65 6. A device is claimed in claim 2, said activating means including a switch having a moveable finger responsively activating and deactivating said switch upon displacement through a predetermined distance, and said piston means including a baffle and a piston rod connecting said baffle with said switch moveable finger.

70 7. A device is claimed in claim 1 further comprising an electric power source and electric motor means driving the knitting machine during the knitting operation 75 wherein said activating means energizes and deenergizes

3,564,874

5

said motor means to start and stop the knitting machine in response to a change in the tube vacuum magnitude.
